UNITED STATES PATENT OFFICE

168,984

COMBINED PNEUMATIC TIRE CASING TRIMMING AND BALANCING MACHINE OR SIMILAR ARTICLE

James H. Braley, Sacramento, Calif.

Application July 28, 1952, Serial No. 20,785

Term of patent 14 years

(Cl. D55—1)

To all whom it may concern:

Be it known that I, James H. Braley, a citizen of the United States, residing at Sacramento, Sacramento County, California, have invented a new, original, and ornamental Design for a Combined Pneumatic Tire Casing Trimming and Balancing Machine or Similar Article, of which the following is a specification, reference being had to the accompanying drawings, forming a part hereof.

Figure 1 is an elevational view of one side of a combined pneumatic tire casing trimming and balancing machine or similar article embodying my new design;

Figure 2 is a top plan view thereof;

Figure 3 is an elevational view of the opposite side of said machine;

Figure 4 is a rear end elevational view; and Figure 5 is a front end elevational view.

I claim:

The ornamental design for a combined pneumatic tire casing trimming and balancing machine or similar article, substantially as shown.

JAMES H. BRALEY.
